(57) **CLAIM**

The ornamental design for a blade of light luminaire, as shown and described.

DESCRIPTION

FIG. 1 is a side elevation view of a luminaire (it is noted that each side elevation view is essentially identical and therefore only one is provided);

FIG. 2 is an end view thereof (it is noted that each end view is essentially identical and therefore only one is provided);

FIG. 3 is a top plan view thereof;

FIG. 4 is a bottom plan view thereof; and,

FIG. 5 is a side perspective view thereof.
